UNITED STATES PATENT OFFICE

99,564

DESIGN FOR A DESK

Benjamin H. Talbert, Evansville, Ind., assignor to Imperial Desk Company, Evansville, Ind.

Application April 2, 1936, Serial No. 61,901

Term of patent 3½ years

To all whom it may concern:

Be it known that I, Benjamin H. Talbert, a citizen of the United States, residing at Evansville, county of Vanderburgh, and State of Indiana, have invented a new, original, and ornamental Design for Desks, of which the following is a specification, reference being had to the accompanying drawing, forming part thereof.

I claim:

The ornamental design for a desk as shown.

BENJAMIN H. TALBERT.
